UNITED STATES PATENT OFFICE.

PARIS ERB, OF LANCASTER, PENNSYLVANIA.

FLUID-PRESSURE REGULATOR.

SPECIFICATION forming part of Letters Patent No. 595,614, dated December 14, 1897.

Application filed October 2, 1896. Serial No. 607,638. (No model.)

To all whom it may concern:

Be it known that I, PARIS ERB, a citizen of the United States, residing at Lancaster, in the county of Lancaster and State of Pennsylvania, have invented certain new and useful Improvements in Automatic Gas-Governors; and I do hereby declare the following to be a full, clear, and exact description of the invention, such as will enable others skilled in the art to which it appertains to make and use the same.

This invention relates to improvements in a gas governor or regulator of that class in which an inverted cup or float with an open 15 end edge submerged constantly to a practically uniform depth in a sealing liquid is adapted, by means of the gas-pressure from the supply-main, to operate over the inlet end a valve in such a manner as to regulate 20 or control the gas-flow from said main to the distributing tubes or pipes and in which provision is made to maintain the submerged edge of the valve-operating float always at a 25 practically uniform depth in said sealing liquid.

The object of the invention is the production at a minimum cost of construction of a simple yet effective gas-governor, whereby the excessive pressure from the gas-main will 30 be utilized to operate a valve over its inlet end, so as to automatically control or regulate the gas-flow that no more gas will be admitted to the distributing pipes or tubes than the burners can readily consume, and to provide 35 an independent disk float or liquid-displacing weight that will constantly maintain a practically uniform depth of sealing liquid about the submerged open edge of the valve-operating float.

40 The elements of the invention will severally and at large appear in the following description and will be separately and collectively set forth in the claim.

The purposes of the invention are attained 45 by the mechanism and devices illustrated in the accompanying drawings, similar reference letters and figures designating similar parts throughout the several views, and in which—

50 Figure 1 is a vertical longitudinal central section of a gas-governor embodying the elements of the invention, showing them in the

positions they assume when there is no excessive pressure from the gas-main. Fig. 2 is a partially-completed view from the right of Fig. 1 with the L-fitting removed from the inlet end. Fig. 3 is a top view of Fig. 2 completed, with portions of the covering-cap, the valve-operating float, and the independent disk float or weight removed; and Fig. 4 is an inverted plan of the disk float detached from Figs. 1 and 3.

A practically L-shaped tubular body A of approved dimensions, comprising two branches A' and A², perpendicular to each other, has rigidly secured to the top of one of said branches, as A', a circular disk or diaphragm A³, and so placed with reference thereto that the other branch A² shall have its axis at the center of said disk and perpendicular therewith, with the outer end of the former branch A' flush or even with the peripheral edge thereof, the branch A² constituting the inlet-tube and the branch A' the outlet. The disk is also provided peripherally with an upwardly-projecting ring flange or wall a, having a prescribed height, and at its center with an upwardly-projecting column or post a', of prescribed dimensions, having at its center an approved axial bore a² for the passage of a valve stem or rod, to be hereinafter described, as well as for the flow of gas therethrough, while the wall is provided exteriorly about its upper or open end with a shallow offset or ring recess a³, having on one side thereof an outwardly-projecting arm with a downwardly-curving lip at its outer end, constituting a side hook a⁴, and on the opposite side thereof is an outwardly-projecting bracket-arm a⁵, having an eye vertically through its body, as shown.

All the parts or elements thus far described are shown to be integrally joined as in one casting, which may be of any approved metal, but cast-iron is preferred, and they constitute the supporting-base of the governor. To cover the same, an inverted cup or cap A⁴, having preferably a flattened circular top with a downwardly-projecting ring flange or wall a⁶, integral therewith at the peripheral edge thereof and exteriorly rounded, as shown, said wall a⁶ having interiorly or at its lower or open end a shallow offset or ring recess fitting onto the ring-recess a³, before men-

tioned, but not so closely as to prevent the passage of air through the joint, being provided exteriorly with a downwardly-projecting staple-bracket or eyed arm A^5 , engaging the hooked arm a^4 , before mentioned, holding the two together at this point, while on the opposite side thereof is an outwardly-projecting bracket-arm A^6 , with a vertical eye through its body, said arm resting on the upper face of the arm a^5 , before mentioned, their eyes registering with each other, through which the shackle of any approved padlock (not shown) may serve to lock them together.

It will here be noted that the elements thus far described constitute the casing of the governor, comprising the L-shaped tubular portion A , before mentioned, and the float-housing chamber A^7 , just completed.

In the outlet end of the branch A' is shown a portion of a tube 1, conducting the gas-flow to the branch or distributing tubes supplying the burners in the usual way, while the inlet end of the branch A^2 , provided with external screw-threads, as shown, is preferably secured into the upwardly-projecting wing of an L-shaped fitting 2, having its other wing screwed onto the end of a horizontally-disposed tube or pipe 3, directly connected with the supply or feed main, so that the gas-flow from said main may not pass in a straight or direct line into the tubular portion A of the governor. Partially driven or embedded into said inlet end, closely fitting, is a tubular ring B , of some soft metal, such as brass, with its projecting end b curving exteriorly, as shown, deflecting the gas-flow downwardly and aiding materially in breaking its direct inflow, while the lower end edge of said ring constitutes a seat, in connection with which a valve, yet to be described, performs its functions.

Now for the purposes of the invention—that is, to open and close the inlet end in the branch tube A^2 , whereby the flow of gas thereto will be under absolute and automatic control—a valve C of approved dimensions and required form is arranged at a prescribed distance from and below the valve-seat before mentioned, but parallel thereto, and in order that said valve may properly perform its functions the center thereof is rigidly secured to the lower end of a valve rod or stem c of required length, which stem, after passing through the bore a^2 before mentioned and through the central orifice c' of a disk float or weight C' , has its upper end rigidly secured through the center to the top of an inverted cup-float C^2 , with the lower or open end edge of its downwardly-projecting peripheral rim, ring-flange, or wall c^2 submerged to the necessary depth in the required mass or quantity of any approved sealing liquid C^3 , covering the entire top surface of the diaphragm A^3 included between its rim-wall a and its central post a' . It will here be noted that the weight or disk float C' is provided with a flat or level bottom face to rest on the mercury, that at its center is an upwardly-pro-

jecting socket or recess c^3 for the reception of the column a' before mentioned, and that the central orifice c' in being engaged by the valve-stem c , as shown, serves to keep said disk diametrically in place.

It will here be observed that the use of mercury or quicksilver as the sealing fluid is preferred in this invention on account of its great specific gravity and on account of its non-liability to evaporate or to oxidize and that the disk or weight float is introduced to keep the depth of its submergence always uniform about the lower or open end edge of the rim-wall c^2 of said float C^2 . The specific gravity of mercury being 13.6 and that of cast-iron 7.1, a ratio practically as of two to one, it will be readily seen that the former will float the latter with about the displacement illustrated in Fig. 1, which also shows the depth to which the rim-wall c^2 of the float C^2 is immersed in the mercury, and to maintain this depth of immersion practically the same the float C^2 , rising or falling in raising or lowering the valve, constitutes the chief feature of this invention, and the importance of which lies in the fact that the float C^2 will always rise or fall under a constant or steady weight, imparting to it a uniform or regular rate of motion.

Now the several elements hereinbefore described and occupying the several positions indicated in the drawings, with the float C^2 weighted in the usual way (well known to the trade) to the degree of gas-pressure at which it should rise, and the gas flowing in the direction indicated by the line of arrows 4, an inspection thereof clearly shows, first, that should there be any excessive pressure from the supply-main, forcing more gas into and through the portion A than the burners will readily consume, said excessive pressure in acting upwardly through the bore a^2 and the orifice c' will exert a lifting force against the under face of the cup-float C^2 and a depressing force on top of the weight or disk float C' ; second, that by reason of said lifting force the float C^2 will rise, raise the valve C , and close the inlet into the branch A^2 in proportion to the degree of said excessive pressure, controlling or regulating the gas-flow accordingly; third, that by reason of said depressing force the weight-float C' will move downwardly and press the mercury from its under face, causing said mercury to rise within the socket c^3 and in the space between its outer vertical face and the wall a of the casting according to the distance of said downward movement; fourth, that by reason of this rising of the mercury in this latter space the depth of submergence of the float ring-wall c^2 will be maintained; fifth, that by reason of the downward force of the excessive pressure on the mercury within or underneath the float C^2 the mercury will rise to a greater height in the narrow space between the walls a and c^2 according to the degree of difference between said excessive pressure

and the atmospheric pressure in said narrow space, and, sixth, that by reason of all these the invention proves to be an automatic gas governor or regulator in which the valve-operating float performs its functions with a steady even motion and under a constant or balanced weight, bringing the gas-flow completely under absolute and automatic control.

Having thus ascertained and described my invention and set forth the manner in which it performs its functions, I lay no claim, broadly, to the diaphragm, the use of mercury in said diaphragm, the inverted cup with its edge immersed in said mercury, nor to the valve 15 with the stem connecting the cup; but

What I do consider new, and desire to secure by Letters Patent, is—

In a gas-governor having a disk diaphragm with an upwardly-projecting peripheral ring-wall and a prescribed column at the center thereof having an axial bore through its body rigidly secured to the top of a tubular por-

tion having an inlet branch and an outlet branch perpendicular to each other with a valve adapted to open and close said inlet branch and an inverted cup with a stem through said axial bore connecting the cup and valve with a quantity of mercury flooding said diaphragm between its peripheral wall and central column and immersing the 25 open end of said inverted cup, a disk weight or float lying independently or unattached on top of said mercury, whereby the gas-pressure coming between the cup and weight in raising the former will depress the latter and displace the mercury from underneath said weight, substantially as described and for the purpose hereinbefore set forth.

In testimony whereof I affix my signature in presence of two witnesses.
